[57] CLAIM

The ornamental design for a loose fill packing element, substantially as shown and described.

DESCRIPTION

FIG. 1 is a side view of a loose fill packing element showing my new design;

FIG. 2 is an end view taken from the right-hand side of FIG. 1;

FIG. 3 is a bottom plan view;

FIG. 4 is an end view from the left-hand side of FIG. 1;

FIG. 5 is a top plan view;

FIG. 6 is a side view showing a modified form of my new design;

FIG. 7 is an end view taken from the right-hand side of FIG. 6;

FIG. 8 is a bottom plan view of the design shown in FIG. 6;

FIG. 9 is an end view from the left-hand side of FIG. 6; and

FIG. 10 is a top plan view of the design shown in FIG. 6.
